[57] CLAIM

The ornamental design for a power and data unit with hemispheres and a central aperture, as shown and described.

DESCRIPTION

FIG. 1 is a perspective view of a power and data unit with hemispheres and a central aperture according to my design; FIG. 2 is a right side elevational view thereof, the left side elevational view being a mirror image thereof; FIG. 3 is a top plan view thereof; FIG. 4 is a front elevational view thereof; FIG. 5 is a rear elevational view thereof; and, FIG. 6 is a bottom plan view thereof.
The broken lines are shown for illustrative purposes only and form no part of the claimed design.
